APPARATUS FOR FEEDING FUEL OIL TO
BURNERS FOR BOILERS AND SIMILAR
INSTALLATIONS

Jesse C. Johnson, Oakland, Calif.

Application December 15, 1934, Serial No. 757,712

5 Claims. (Cl. 137—78)

This invention is an apparatus for feeding fuel oil to burners for boilers and similar installations.

One of the objects of the invention is to provide a feeding apparatus for fuel oil, so designed, constructed and arranged as to insure a regular, continuous and uniform flow of fuel oil to the burner atomizer. A further object is to adequately regulate the feed of oil at the starting of the burner operation. A further object is to provide a multiple-stand-pipe oil reservoir connected with the feed line to the burner, in such manner as to provide a gravity feed to the burner, said feed being controlled by the use of a motor-operated pumping system. Another object is to provide means for freeing any air which may have been trapped in the oil, before it is delivered to the burner.

The invention will be hereinafter fully set forth and particularly pointed out in the claims.

20 In the accompanying drawings:—

Figure 1 is a top plan view, partly in section, illustrating a fuel feeding apparatus constructed in accordance with the invention. Figure 2 is a side elevation with the multiple-stand-pipe shown in longitudinal section. Figure 3 is a vertical elevation of the multiple-stand-pipe and siphon breaker. Figure 4 is an enlarged detail sectional view of a portion of the multiple-stand-pipe member. Figure 5 is a vertical sectional view of the siphon breaker.

Referring to the drawings, 10 conventionally designates the boiler to be heated by the burner, the same being mounted upon legs 11, only one of which is shown. The burner motor 12 is centrally located beneath the bottom of the boiler 10 and drives the usual atomizer (not shown) in the boiler fire box. As is well known in the art, the atomizer serves to atomize the oil as it is fed to the burner, by a rotating part travelling at high speed. At the bottom of the burner motor 12 is the usual centrifugal pump 13 of the type provided with a hollow motor shaft, and through which the oil passes to feed the atomizer in the fire box in a manner well understood in the art. The pump 13 is connected with a tank 15 by means of a supply pipe 16 which is connected with a strainer 17, the strainer in turn being connected with a lower chamber in the pump casing, by means of a conduit 18. The parts thus far described, are all of standard construction in common use and are not herein claimed, except insofar as they are necessary to the operation of the invention here involved. Leading from the chamber in the bottom of the pump casing is a conduit

19 which discharges into the multiple-stand-pipe member M.

The multiple-stand-pipe member consists of a supporting casting 20 provided with a receiving chamber 21 formed by a transverse partition 22 which is provided with a central threaded opening. Above the chamber 21 the casting 20 is provided with a delivery chamber 23 and an overflow chamber 24. Extending upwardly from the partition 22 through the chambers 23 and 24, and communicating with the chamber 21, is a pipe or conduit 25. Extending upwardly from the partition wall 26 which divides members 23 and 24, is a larger conduit 27, the lower end of which communicates with the chamber 23, said conduit 27 being concentric with and enclosing the conduit 25. It will be noted that the conduit 27 extends above the end of the conduit 25 a substantial distance as indicated at 28.

Leading from the top of the casting 20 is a 20 larger conduit 29 concentric with the conduits 25 and 27 and enclosing the same, said conduit 29 communicating with the overflow chamber 24. It will be noted that the conduit 27 is provided with a bleed opening controlled by a valve 30. The 25 supply chamber 23 is connected with a magnetic valve 31 of the usual type, by means of an outlet conduit 32, and said magnetic valve is connected with the hollow shaft of the burner by means of a conduit 33. The overflow chamber 24 is connected by means of an overflow pipe 34 with the tank 15. It will be noted that the conduit 29 extends a substantial distance above the upper end of the conduit 27, as indicated at 35 and is closed by a cap 36.

The siphon breaker consists of a casing 40 having an inlet opening 41 communicating with the interior of the cap 36. The top 42 of the casing 40 is removable and is provided with an air discharge conduit 43. Within said conduit is located 40 a valve seat 44 which is complementary to a needle valve 45 provided with wings 46 which rest upon a float 47, the float is guided in its movement by a fixed stem 48.

In operation, when the current is turned on 45 to the burner motor in the usual manner, the pump motor is energized and the magnetic valve is energized. As a result, oil will be drawn from the tank 15 through the pipe 16 and strainer 17 and then through the chamber beneath the pump 50 casing, being then delivered to the receiving chamber 21. From the receiving chamber the oil travels upwardly through conduit 25 and overflows at the upper end thereof within the space 28 of the conduit 27. The oil will then 55

flow downwardly into the delivery chamber 23 and from thence to the hollow shaft of the pump and then into the burner atomizer in a well known way. It will be noted that while the oil is being pumped through the conduit 25, a larger amount of oil will overflow from said conduit than is necessary to support the burner flame. The surplus oil flows over the top of the conduit 27 and drops into the overflow chamber 24 and will then be returned to the tank through conduit 34. The object of the bleed hole controlled by the valve 30 is to cause an early overflow of the oil as it passes down between the conduits 25 and 21, so that only a small quantity of oil at low pressure, for a short period of time, will reach the burner after the burner motor is first started. The size of the bleeder will be controlled by the valve 30. Only a stoppage of conduit 34 could cause oil to flow into extension 35 and into chamber 40. As the oil flows up into the extension 35, it will also eventually overflow into the chamber 40 so that the float 47 is lifted so as to seat the valve 45 to prevent escape of the oil and to confine it in such manner that the overflow will be returned to the tank. As soon as the pressure of the overflow is reduced, the float 47 will drop and open the vent 43 so that air is permitted to enter the upper part of the stand-pipe and counteract any tendency of the downflowing oil in the conduit 29 to create siphon and rob the burner of fuel.

The advantages of the invention will be readily understood by those skilled in the art to which it belongs. For instance, it will be particularly noted that the device is so constructed and arranged as to provide a continuous and uniform flow of fuel to the burner atomizer at a gravity pressure and in such manner that the starting of the burner operation is greatly facilitated. An important advantage of the multiple-stand-pipe construction is that a uniform gravity feed of the oil is provided and at the same time any tendency to produce a siphonic action to a sufficient extent to rob the burner is completely prevented. Having thus explained the nature of the invention and described an operative manner of constructing and using the same, although without attempting to set forth all of the forms in which it may be made, or all of the forms of its use, what is claimed is:—

1. In an apparatus for feeding fuel oil, a multiple column stand-pipe comprising a base provided with an inlet chamber having an inlet opening, an outlet chamber having an outlet opening, and an overflow chamber having an outlet opening, a supply conduit leading from said inlet chamber, a discharge conduit concentric with the first conduit and connected with the outlet chamber, an overflow conduit concentric with the other conduits and connected with the overflow chamber, said discharge conduit extending higher than the supply conduit but not so high as the overflow conduit, and means for venting said discharge conduit into said overflow conduit intermediate the ends of said discharge conduit.

2. In an apparatus for feeding fuel oil, a multiple column stand-pipe comprising a base provided with an inlet chamber having an inlet opening, an outlet chamber having an outlet opening, and an overflow chamber having an outlet opening, a supply conduit leading from said inlet chamber, a discharge conduit concentric with the first conduit and connected with the outlet chamber,

ber, and an overflow conduit concentric with the other conduits and connected with the overflow chamber, said discharge conduit extending higher than the supply conduit but not so high as the overflow conduit, said conduits having upper free ends with the upper free end of the supply conduit terminating within the discharge conduit, said discharge conduit having a bleed opening therein. 5

3. In an apparatus for feeding fuel oil, a multiple column stand-pipe comprising a casting provided with an upper open end and two relatively spaced partitions, providing an inlet chamber having an inlet opening, an outlet chamber having an outlet opening, and an overflow chamber having an outlet opening, a supply conduit leading upwardly from the inlet chamber, a discharge conduit concentric with the first conduit and leading upwardly from the outlet chamber, an overflow conduit connected with the open end of said casting and leading upwardly therefrom, said discharge conduit being located within the overflow conduit and connected with the supply chamber through one of said partitions, the supply conduit being located within the discharge conduit and connected with the supply conduit through the other of said partitions, said conduits being in communication with each other at their upper ends, and said discharge conduit and overflow conduit being in communication with each other intermediate their ends. 10 15 20

4. In an apparatus for feeding fuel oil, a multiple column stand-pipe comprising a base provided with an inlet chamber having an inlet opening, an outlet chamber having an outlet opening, and an overflow chamber having an outlet opening, a supply conduit leading from said inlet chamber, a discharge conduit concentric with the first conduit and connected with the outlet chamber, and an overflow conduit concentric with the other conduits and connected with the overflow chamber, said discharge conduit extending higher than the supply conduit but not so high as the overflow conduit, said discharge conduit having a bleed opening therein, 25 30 35 and a cap closing the upper end of said overflow conduit.

5. In an apparatus for feeding fuel oil, a multiple column stand-pipe comprising a base provided with an inlet chamber having an inlet opening, an outlet chamber having an outlet opening, and an overflow chamber having an outlet opening, a supply conduit leading from said inlet chamber, a discharge conduit concentric with the first conduit and connected with the outlet chamber, an overflow conduit concentric with the other conduits and connected with the overflow chamber, said discharge conduit extending higher than the supply conduit but not so high as the overflow conduit, said conduits being in communication with each other at one end thereof, said discharge conduit being provided with an opening of variable area intermediate its ends for permitting flow of fluid contained in said conduit into said overflow conduit, 55 60 65 70 75 80 85 90 95 a chamber connected with the upper end of the overflow conduit, a chamber communicating with said overflow conduit and having a vent opening therein, and a float valve controlling said vent opening and so constructed and arranged to prevent siphonic action of the oil in the overflow pipe when feeding pressure upon the oil is reduced.
